UNITED STATES PATENT OFFICE.

VICTOR J. GARVIN, OF CHICAGO, ILLINOIS.

MERCHANDISING COUPON.

Application filed September 26, 1924. Serial No. 739,995.

My invention relates to improvements in merchandising coupons, and has for its object the provision of an improved construction of this character arranged to 5 greatly facilitate merchandising and similar transactions by the use thereof.

Other objects will appear hereinafter.

The invention consists in the combinations and arrangements of parts hereinafter 10 described and claimed.

The construction will be best understood by reference to the accompanying drawing which is a plan view of a merchandising coupon embodying the invention.

15 The preferred form of construction as illustrated in the drawings comprises a coupon in the form of an elongated sheet or strip of paper printed at one end to constitute an obligation 1. This obligation is 20 for a limited time and contains in general the name of the obligor and an agreement to recompense the obligee for services rendered, the services contemplated in the example exemplified in the drawing consisting 25 in obtaining customers for the sale of coal. Arranged at the inner end of the obligation 1 is an introductory section 2 provided with two blank lines 3 and 4, accompanied by appropriate printed matter for the insertion of the name of the obligee and also the name of the introducer. A detachable stub 5 is arranged at the other end of the strip or coupon 1 and a line of perforations 6 provided to facilitate detachment. The 30 stub 5 contains proper printed matter to constitute the same an obligation to recompense the introducer for services in introducing or interesting the obligee contemplated in the obligation 1. The stub 5 and the obligation 1 both bear the same identifying number 7.

In use the coupons are distributed usually to customers or those occupying a similar relation, the object being to induce one customer to obtain others and be recompensed therefor. When a customer has interested another in the proposition he fills in the other's name on the line 3 and his own name on the line 4, detaches the stub 5 and 45 hands the obligation 1 to the new proposed customer, the stub 5 being retained in order that the recompense or commission provided for therein may be obtained in accordance with the agreement indicated.

While I have illustrated and described 55 the preferred form of construction for carrying my invention into effect, this is capable of variation and modification without departing from the spirit of the invention. I, therefore, do not wish to be limited to 60 the precise details of construction set forth, but desire to avail myself of such variations and modifications as come within the scope of the appended claims.

Having described my invention, what I 65 claim as new and desire to secure by Letters Patent, is:

1. A merchandising coupon comprising a section consisting of an obligation to pay for services rendered and containing the 70 name of the obligor; an introductory section provided with a blank appropriately designated for the insertion of the name of the obligee in said obligation and the name of an introducer; and a detachable stub constituting an obligation to recompense the introducer, said stub and section having corresponding identifying indicia thereon, substantially as described.

2. A merchandising coupon comprising a 75 sheet of paper printed at one end to constitute an obligation to pay for services rendered and containing the name of the obligor; blank lines at the inner end of said obligation appropriately designated for the 80 insertion of the name of the obligee and also the name of an introducer; and a detachable stub at the inner end of said obligation, said stub being printed to constitute an obligation to recompense the introducer, said stub and first mentioned obligation having corresponding identifying indicia thereon, substantially as described.

3. A merchandising coupon comprising 85 an elongated strip of paper printed at one end to constitute an obligation to pay for services rendered, containing the name of the obligor and being complete without insertion; blank lines arranged transversely at the inner end of said obligation and appro- 100 priately designated for the insertion of the name of the obligee of said obligation and also the name of an introducer; and a detachable stub at the inner end of said obligation, said stub being printed to constitute an obligation to recompense the bearer and being complete without further insertion, said stub and first mentioned obligation having corresponding identifying indicia thereon, substantially as described.

In testimony whereof I have signed my name to this specification.

VICTOR J. GARVIN.